(57) **CLAIM**

I claim the ornamental design for a wedge-shaped container, as shown and described herein.

DESCRIPTION

FIG. 1 is a top, rear perspective view of my wedge-shaped container;

FIG. 2 is a front, bottom perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top view thereof; and,

FIG. 8 is a bottom view thereof.

In the drawings, the broken lines are for the purpose of illustrating environment only and form no part of the claimed design.

1 Claim, 4 Drawing Sheets(56)
